UNITED STATES PATENT OFFICE

103,305

DESIGN FOR A MERCHANTISE DISPENSING STAND

Jacob Caplan, Chicago, Ill.

Application December 28, 1936, Serial No. 66,771

Term of patent 14 years

To all whom it may concern:

Be it known that I, Jacob Caplan, a citizen of the United States, residing at Chicago, in the county of Cook and State of Illinois, have invented a new, original, and ornamental Design for a Merchandise Dispensing Stand, of which the following is a specification, reference being had to the accompanying drawing, forming a part thereof.

I claim:

The ornamental design for a merchandise dispensing stand substantially as shown.

JACOB CAPLAN.
